US00D764127S

(12) **United States Design Patent**
Vicari et al.

(10) **Patent No.:** **US D764,127 S**
(45) **Date of Patent:** **** Aug. 16, 2016**

(54) **SQUEEGEE**

(71) Applicants: **Joern Vicari**, Brooklyn, NY (US);
Mason Adam Umholtz, Brooklyn, NY (US);
Lingxiu Wu, Brooklyn, NY (US);
Cindy Godin, New York, NY (US)

(72) Inventors: **Joern Vicari**, Brooklyn, NY (US);
Mason Adam Umholtz, Brooklyn, NY (US);
Lingxiu Wu, Brooklyn, NY (US);
Cindy Godin, New York, NY (US)

(73) Assignee: **HELEN OF TROY LIMITED**, St. Michael (BB)

(**) Term: **14 Years**

(21) Appl. No.: **29/526,488**

(22) Filed: **May 9, 2015**

(51) LOC (10) Cl. **04-01**

(52) U.S. Cl.

USPC **D32/41**

(58) **Field of Classification Search**

USPC D32/40-42, 46-49; D8/33, 47, 90, 93;

D4/118, 199; D24/146-147

CPC A47L 1/06; A47L 13/24

Primary Examiner — John Windmuller

Assistant Examiner — John R Yeh

(57) **CLAIM**

The ornamental design for a squeegee, as shown and described.

DESCRIPTION

FIG. 1 is a perspective view of the squeegee shown in a broken away configuration;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines represent portions of the squeegee that form no part of the claimed design.

The squeegee is shown broken away in the middle to indicate that it has no specific length other than what is shown.

1 Claim, 7 Drawing Sheets
